UNITED STATES PATENT OFFICE.

GEORGE W. PIERCE, OF CAMBRIDGE, MASSACHUSETTS, ASSIGNOR TO SUBMARINE SIGNAL COMPANY, OF PORTLAND, MAINE, A CORPORATION OF MAINE.

ELECTRIC RETARDATION LINE.

Application filed December 24, 1921. Serial No. 524,807.

To all whom it may concern:

Be it known that I, GEORGE W. PIERCE, a citizen of the United States, residing at Cambridge, Middlesex County, Massachusetts, have invented a new and useful Improvement in Electric Retardation Lines, of which the following is a full, clear, and exact description.

The present invention relates to electric retardation lines, and more particularly to a retardation line for introducing definite time retardation of electric currents in a manner such that currents of a complex character will be retarded in a rational and predeterminable way, without essential distortion, over a significant range of frequencies. The present invention results in a considerable extension over previous retardation lines the range of frequencies for which the retardation time is independent of frequency.

The present invention is an improvement over the artificial retardation line disclosed in my pending application, Serial No. 306,689½, filed June 25, 1919, for electric compensators. The present invention, however, is not limited to the application of the retardation line herein disclosed, to an electric compensator, as the present invention is capable of wider application and may be employed wherever an artificial line is desired which will retard electric currents without essential distortion over a considerable range of frequencies.

In my application for electric compensators I showed an artificial line consisting of inductance elements in series and capacity elements in shunt for introducing predetermined elements of time retardation into electric currents transmitted through the artificial line.

The present invention relates particularly to the introduction into such a line of mutual induction between the inductance elements,—said mutual inductance being properly proportioned to the self-inductance of the elements. I have discovered that the mutual inductance between inductive elements, or coils, of such a line, if given a certain unique relation to the self-inductance of the inductance elements, greatly extends the range of frequencies for which the retardation time is independent of, or little dependent on, the frequency of the electric currents. The artificial line construction

of the present invention permits the retardation by a fixed time or by a time variable at will by known or predetermined amounts, which retardation may be introduced into a current of complicated wave form with a greatly reduced dispersion of the complicated wave by unequal retardation of the separate frequency components of the complicated wave form. I employ the term "low dispersion" or "substantially dispersionless" herein as descriptive of a line or system through which a complicated wave form may pass and be essentially preserved in its wave form in that the different significant frequency components of the wave form pass with essentially equal time retardations. The significant frequency components are those which are necessary or desirable in the electric current for the purposes employed. For example, in electric current of audible frequency used in connection with auditory translating devices, such as telephone receivers, the significant frequency components of the wave form are the audible or principal audible frequency components.

In the drawings, Figure 1 is a diagram showing an artificial line illustrating the present invention; and Figure 2 is a detail view in section indicating diagrammatically a mounting of the inductance coils.

Referring to the diagrammatic illustration of the invention, an artificial line is illustrated having two sides or wires 1 and 2. For convenience the left hand side marked A may be considered as the input and the right side marked B the out put end of the section of the line which contains the retardation sections. The retardation line is made up of a plurality of recurrent sections each comprising an inductance 3 in series with the line and a capacity 4 shunted across the line. In the diagrammatic illustration five sections are illustrated, it being understood, however, this is merely for the purpose of illustration and that in practice the number of sections will generally considerably exceed this, depending of course upon the purposes for which the line is used and the amount of time retardation desired. When the retardation line is to be used in an electric compensator as shown, for example, in my electric compensator application Serial No. 306,689½ referred to above, the line will be provided with the necessary taps and con-

5 tacts whereby the number of effective sections may be varied at will. The inductance coils 3 are preferably placed end to end, and may be wound on a common core, as indicated schematically in Figure 2. The showing in Figure 2 is intended merely as a general diagrammatic illustration and it will be understood that in winding and mounting the coils, the diameter of the coils, the 10 size of wire, the spacing of the coils apart, etc., will be calculated in accordance with the formulae hereinafter referred to. The windings of adjacent coils are so spaced from one another that the mutual inductance between adjacent coils 3 is approximately one-tenth of the self-inductance of each coil. The computation of this 1 to 10 relation is based on the following considerations.

Let L_1 be the self-inductance of each of 20 the inductance coils.

15 M be the mutual inductance between adjacent coils, and, as notation, let

25

$$L = L_1 + 2M, \quad (1)$$

$$\eta = R/L\omega, \quad (2)$$

where ω = the angular velocity of a sinusoidal 30 electromotive force impressed at the input end of the line, and, as further notation, let

$$Q = \frac{LC_2\omega^2}{1+MC_2\omega^2}, \quad (3)$$

35

then, we have

$$a = \sinh^{-1} \left\{ \sqrt{\frac{Q}{2}} \sqrt{\pm \sqrt{\eta^2 + \left\{ 1 - \frac{Q}{4}(1 + \eta^2) \right\}^2} - \left\{ 1 - \frac{Q}{4}(1 + \eta^2) \right\}} \right\} \quad (4)$$

$$\phi = \sin^{-1} \left\{ \sqrt{\frac{Q}{2}} \sqrt{\pm \sqrt{\eta^2 + \left\{ 1 - \frac{Q}{4}(1 + \eta^2) \right\}^2} + \left\{ 1 - \frac{Q}{4}(1 + \eta^2) \right\}} \right\} \quad (5)$$

40 In equations (4) and (5) a is the attenuation constant and ϕ the retardation angle introduced by the line into the current per section of the line. The same sign must be employed before the inner radical in the two equations, and that sign must be selected to 45 make a and ϕ both real quantities. The equations (4) and (5) are exact.

If now we temporarily let

$$A = 1 - \frac{Q}{4}(1 + \eta^2), \quad (6)$$

50

take the sine of both sides of (5), square both sides, and expand the result in series for values of A^2 greater η^2 , we obtain

$$\frac{1}{2} \left\{ \frac{(2\phi)^2}{2!} - \frac{(2\phi)^4}{4!} + \frac{(2\phi)^6}{6!} - \dots \right\} = QA \left\{ 1 + \frac{\eta^2}{4A^2} - \frac{\eta^4}{16A^4} + \dots \right\}. \quad (7)$$

55 Let us now introduce the limitation that in any practical case of importance to the present invention $\eta^4/16A^4$ is negligible in comparison with unity, and let us expand $1/A$ into

$$1 + \frac{Q}{4}(1 + \eta^2) + \frac{Q^2}{16}(1 + \eta^2)^2 + \dots$$

60

and write (7) in the form

$$\frac{1}{2} \left\{ \frac{(2\phi)^2}{2!} - \frac{(2\phi)^4}{4!} + \frac{(2\phi)^6}{6!} - \dots \right\} = Q - \frac{Q^2}{4} + \frac{\eta^2 Q^2}{16} + \frac{\eta^4 Q^2}{16} + \frac{\eta^2 Q^3}{64} + \dots \quad (9)$$

Let us now expand Q , as defined by equation (3), in the form

$$Q = F(1 - G - G^2 - \dots), \quad (10)$$

$$F = LC_2\omega^2, \text{ and } G = MC_2\omega^2. \quad (11)$$

Now substituting (10) into (9), and keeping only significant terms, we obtain

70

$$\varphi^2 - \frac{\varphi^4}{3} + \frac{2\varphi^6}{45} - \dots = F - \left[FG + \frac{F^2}{4} - \frac{\eta^2 F^2}{16} \right] - \left[FG^2 - \frac{F^2 G}{2} + \frac{\eta^2 F^2 G}{8} \right] + \dots \quad (12)$$

In order to make the time retardation independent of frequency, it is necessary to make the retardation angle φ proportional to ω ; and since F is proportional to ω^2 , equation (12) suggests the advisability of making

$$\varphi^2 = F, \quad (13)$$

$$10 \quad \frac{\varphi^4}{3} = \frac{F^2}{3} = FG + \frac{F^2}{4} - \frac{\eta^2 F^2}{16}, \quad (14)$$

and

$$15 \quad \frac{2\varphi^6}{45} = \frac{2F^3}{45} = -\left\{ FG^2 - \frac{F^2 G}{2} + \frac{\eta^2 F^2}{16} \right\}. \quad (15)$$

It is seen that (14) leads to

$$G = F \left\{ \frac{1}{12} + \frac{\eta^2}{16} \right\}, \quad (16)$$

20 and that (15) is sufficiently nearly satisfied by the same value of G .

For coils constructed with ordinary care as to resistance the term $\eta^2/16$ in equation 25 (16) may be usually neglected, and under these conditions (16) gives, in view of (11)

$$M = L/12, \text{ approximately.}$$

If now we replace L by its value from (1), we obtain

$$M = L_1/10, \text{ approximately.} \quad (17)$$

30 Therefore, if we make the line to have between neighboring coils a mutual inductance, as given by (17), approximately equal to one-tenth of the self-inductance of each coil, we shall have the effect that the range 35 of frequencies over which the time retardation per section is essentially independent of the frequency is much greater than the range with M equal to zero as in the practice heretofore. In fact the specific value 40 of M given by equation (17) is uniquely the best value to give to M to make the line one of low dispersion.

45 Equation (17) is stated only approximately, in that this value may be shifted slightly one way or the other to make slight adjustments for some of the small neglected terms. Also in practice, it may be desirable for structural reasons to depart somewhat from (17).

50 To obtain the time retardation T per section of the line, it is only necessary to divide the retardation angle φ by the angular velocity ω . By (13) and (11) this operation gives for a significant range of 55 frequencies

$$T = \sqrt{(L_1 + 2M)C_1} = \sqrt{6L_1 C_2/5}, \quad (18)$$

provided $M = L_1/10$.

The principles of the above mathematical 60 discussion are to be found in my book entitled Electric Oscillations and Electric Waves published by McGraw-Hill Book Co. Inc. New York, 1920, and particularly in Chapter XVI and specifically on page 316 65 and following. On page 316 of this book,

in line 3 of section 283, of the first impression, the words "and if there is no magnetic leakage" should be stricken out, as I have found that the results are general. Reference may be made to this book for details 70 of the principles above treated.

It will be noted that the present invention constitutes a transmission line of low dispersion, and in addition to this important feature it has the advantage of being easier 75 and cheaper to construct than a line without the novel feature of properly proportioned mutual inductance, in that the coils may be wound in solenoidal form and may be compactly arranged which obviates the 80 expense of toroidal windings or of wide spacing as must be employed in artificial lines not having my novel features.

It will be seen by computation or experiment that a slight departure, for example 10 percent, from the relation $M = L_1/10$ 85 may be made with only slight departure from the low dispersive effect of the line.

For general computations as to attenuation, retardation, and surge impedance of the line and apparatus of the present invention use may be made of sections 283, 284 and 285 of my book above referred to, which sections are contained on pages 316 and following. In using these sections for calculation of apparatus of the present invention, the value $M = L_1/10$, or in case of a small departure from this relation the value of M specifying the departure, should be employed and substituted into the formulas 90 of the book. 95

100 By having the induction coils with the mutual inductance relation as specified in this application, the range of frequencies for which the dispersion is low and practically insignificant may be from three to ten times as great as the range for lines without the mutual inductance. As above pointed out the present invention, however, is not limited to the use of a retardation line in an electric compensator shown in my electric compensator application, but the apparatus and method of the present invention is one of general application. It is to be understood that the present invention is not so 110 broadly as set forth in the following claims: 115

I claim:

1. An electric retardation line having capacities in shunt and inductance elements in series and having the mutual inductance between adjacent inductance elements approximately equal to one-tenth of the self-inductance of the elements, substantially as 125 described.

2. An electric retardation line having capacities in shunt and inductance elements in series, having the self-inductance between 130 neighboring points of attachment of the ca-

pacities approximately ten times the mutual inductance between the inductance elements, substantially as described.

3. An electric retardation line having low distortion and comprising capacities in shunt and inductance coils in series having their self and mutual inductances so proportioned that the line is substantially dispersionless as well as of low distortion over a considerable range of significant frequencies, substantially as described.

4. An electric retardation line comprising a series of recurrent sections each comprising a capacity shunted across the line and an inductance coil in series with the line and so located with relation to adjacent sections as to have mutual inductance therewith in the neighborhood of one-tenth of its self-inductance, substantially as described.

5. An electric retardation line comprising a series of recurrent sections, each having a capacity shunted across the line and an inductance in series with the line permitting the substantially free passage of alternating

currents to the output terminals of the line, the inductances of adjacent sections being so located with respect to each other as to have such mutual inductance as to minimize dispersion of the significant frequency components of the current waves, substantially as described.

6. An electric retardation line having capacities in shunt and inductance coils in series, the inductance coils each having substantially the same self-inductance and each pair of adjacent coils having substantially the same mutual inductance, the self and mutual-inductance being so proportioned that the line is substantially dispersionless over a considerable range of frequencies, substantially as described.

7. An electric retardation line comprising a series of recurrent sections, each comprising a capacity shunted across the line and an inductance in series with the line so located as to have mutual inductance with the inductance coils of adjacent sections in substantial accordance with equation

$$\phi = \sin^{-1} \left\{ \sqrt{\frac{Q}{2}} \sqrt{\pm \sqrt{\eta^2 + \left\{ 1 - \frac{Q}{4}(1 + \eta^2) \right\}^2} + \left\{ 1 - \frac{Q}{4}(1 + \eta^2) \right\}} \right\},$$

so that the retardation angle is approximately proportional to the angular velocity over the significant range of frequencies, substantially as described.

8. An electric retardation line comprising a series of recurrent sections, each including a capacity shunted across the line and an inductance in series with the line and whose retardation angle per section is an antisine

function of the frequency of the impressed electromotive force, the inductances of adjacent sections being so located with respect to each other as to reduce said retardation angle to substantial proportionality to said frequency, substantially as described.

In testimony whereof I have hereunto set my hand.

GEORGE W. PIERCE.
